UNITED STATES PATENT OFFICE.

MARK COPPINGER, OF KANSAS CITY, MISSOURI.

DESIGN FOR A COMBINATION LAMP AND STREET-SIGN.

51,774.

Specification for Design.

Patented Feb. 12, 1918.

Application filed September 20, 1917. Serial No. 192,417. Term of patent 14 years.

To all whom it may concern:

Be it known that I, MARK COPPINGER, a citizen of the United States, residing at Kansas City, in the county of Jackson and State of Missouri, have invented a new, original, and ornamental Design for a Combination Lamp and Street-Sign, of which the following is a specification, reference being had to the accompanying drawing, in which—

Figure 1 is an elevation of a combination

lamp and street sign, showing my new design.

Fig. 2 is a plan view thereof.

I claim:

The ornamental design for a combination lamp and street sign, as shown.

MARK COPPINGER.
